2 Claims. (Cl. 16—18)

1

This invention relates to caster wheels and has particular though not specific reference to caster wheels for use with articles of furniture to provide freedom of movement of the same upon a floor or like supporting surface.

Caster wheels or casters of the usual swiveling type commonly used on articles of furniture have certain disadvantages, mainly arising from the necessarily small dimensions of the rollers, which sink into and depress the surface of a carpet or floor covering and thus impede free and smooth running of an article of furniture. Moreover, the small rollers cause undue wear and damage of the carpet or floor covering, particularly if the article is subjected to frequent movement.

If the roller be increased in size to avoid such disadvantages, the caster increases in height to an abnormal extent and becomes unduly large and bulky. Moreover, the distance of the axis of the roller from the vertical pivotal axis of the caster is correspondingly increased, thus augmenting the leverage effect of the weight on the roller upon the pivotal axis and tending to cause binding and excessive frictional resistance to swivelling movements, thereby adversely effecting the sensitivity of self-alignment of the caster.

In order to avoid these disadvantages, casters have been previously devised in which rollers of substantially hemispherical construction were provided. Such rollers are advantageous in that they may be of relatively large size without increasing the dimensions of a caster in general.

Casters having hemispherical rollers rotatably mounted in inclined bearings offset from and adapted to swivel about vertical axes have been proposed, but such rollers had disadvantages in that lubricant could not be retained in the offset bearings. Moreover, in such previously known casters, the hemispherical rollers had an unduly large surface contact particularly upon carpets having thick piles, so much so, that castering movements were restrained and considerable effort was necessary to propel articles of furniture to which the casters were fitted.

The principal object of this invention is to provide a compact caster of hemispherical roller type and of neat appearance having great mechanical strength and free running characteristics and having a supporting wheel or roller of considerably greater diameter than the usual roller, while eliminating the above recited disadvantages of casters of usual type or construction.

Another object of the invention is to so arrange and construct the inclined axis about which the hemispherical roller rotates, that the rotating bearing surface of the latter is continuously lubricated, and is so disposed that lubricant

is retained and does not require replenishment for long periods of time.

A further object is to construct the hemispherical roller in such a manner that the floor contact surface is reduced by the provision on the roller of an outstanding peripheral tread or band of relatively large diameter.

The invention will be better understood from the following description of the exemplary arrangement shown in the accompanying drawings.

In these drawings:

Figure 1 is an elevation of a caster suitable for attachment to an article of furniture.

Figure 2 is a sectional elevation of the caster shown in Figure 1 with a portion removed for clearer illustration.

Figure 3 is a section on the line 3—3 in Figure 2.

Figure 4 illustrates a detail of the invention.

In these drawings, the numeral 6 indicates a fixing plate for attachment to a leg or other part of an article of furniture (not shown), and 7 a spindle rigidly secured to the plate 6 and arranged to depend vertically from the same.

The spindle 7 extends vertically through an aperture 8 in a substantially hemispherical cup member 9 which is associated, as hereinafter described, with a complementary cup member 10, likewise of substantially hemispherical formation, which comprises the supporting roller of the caster and is provided with a peripheral floor-engaging part or tread rim 10a.

The tread rim 10a is integral with the cup member 10, and the former comprises a segmental portion of a sphere of greater radius than the body part of the member 10.

The interior of the tread rim 10a is recessed to receive the marginal edge of the cup member 9, a small clearance being provided between the surfaces of the recess and the cup member.

It will be observed and understood that the cup members 9 and 10 when assembled, comprise a substantially spherical shell, which is sealed against entry of dust and dirt except for the small clearances provided between the edges of the cup members and between the spindle 7 and aperture 8.

The spindle 7 fits within a hole 11, formed in a block 12, the hole 11 being cylindrical to provide an upright bearing for the spindle 7 and being closed at the lower end 13 to form a foot step or thrust bearing to support the weight imposed upon the plate 6, see Figure 2. In order to provide a freely movable thrust bearing of low frictional resistance, the lower end of the spindle 7 is pointed as at 14, and the closed end 13 of the bearing hole 11 is formed conically, as at 15, the included angle of the conical end of the hole 11 being more obtuse than the included angle of

the pointed end 14, thereby providing a space 16 to contain lubricant.

Formed integrally with the block 12 is an inclined lug 17, through which extends transversely a tapped hole 18 into which is screwed a spindle or axle 19 having a head 20 formed appropriately for spanner engagement.

The axle 19 when mounted in the lug 17 is inclined to horizontal and is spaced apart or offset from the vertically dependent spindle 7, and it will be apparent that this disposition of the axle 19 will be maintained in all rotative positions of the block 12 and the lug 17 about the spindle 7, see Figures 2 and 3.

The cup member 9 is secured to the axle 19 by a screw 21 passed through said member into engagement with a tapped hole 22 in the head 20.

The supporting roller 10 has an internal boss 23 axially bored at 24 to fit the axle 19, so that the roller 10 is journalled upon and rotates about the inclined axle 19 in passing over a floor surface.

The end of the axle 19 is pointed and the inner end of the hole 24 is made of conical formation similarly to the vertical spindle 7 and hole 11, as and for the purposes previously described.

Fixed to the inclined lug 17, as by screws 25, is a retaining plate or member 26 which serves the dual purposes of retaining the block 12 upon the vertical spindle 7 and the supporting roller 10 on the axle 19.

For the latter purpose the plate 26 is recessed at 27 to accommodate a flange 28 on the boss 23, and said plate is formed with a flange 29 which projects into a peripheral groove 30 on the boss 23. Accordingly, the flange 28 is retained between the lug 17 and the flange 29 to prevent displacement of the boss 23 from the axle 19. The recess 27 and the groove 30 are made of somewhat greater widths than the flanges 28 and 29 to provide sufficient clearance to ensure that end thrust is supported by the pointed end of the axle 19.

For the purpose of preventing displacement of the block 12 from the vertical spindle 7, the latter is provided with a peripheral collar 31 which is engaged by an overlying lug 32 formed on an extension 33 of the retaining plate 26.

The hemispherical supporting roller 10 and the relatively fixed hemispherical cup member 9 comprise in combination a hollow spherical shell enclosing the vertical and inclined bearings. Access to the bearings for lubrication or repair is readily obtained upon withdrawal of the screw 21, whereupon the cap member 9, which forms a cover of the spherical shell, may be removed. Upon removal of the cup member or cover 9, the screws 25 may be taken out, thereby releasing the retaining plate 26 to set free for removal the block 12 from the spindle 7 and the roller 10 from the axle 19.

The closed end bearings 11 and 24 as above described enable them to be charged with lubricant during assembly of the caster and the bearings provide a reservoir for the lubricant and self lubrication for the spindle 7 and axle 19.

It will be apparent that lubricant cannot escape from the hole 11 and the axially bored boss 23, so that the caster will function efficiently for long periods without replenishment of lubricant.

In use, and as a consequence of the comparatively large diameter of the supporting roller and the closeness of its axle to the vertical swivel axis, a caster constructed as described travels easily over a supporting surface and readily

tracks with and follows the direction of travel of an article of furniture to which it is attached. Moreover, the complete enclosure of the bearings excludes dust from the same, while the provision for lubrication ensures a maximum of service. Furthermore, the provision of the rim tread or outstanding band of relatively large diameter on the hemispherical roller prevents unduly deep penetration of the roller into a carpet having a thick pile and assists the castering action.

I claim:

1. A caster comprising a rotatable hemispherical roller having its edge portion enlarged to form a peripheral floor-engaging tread and a recess within said enlarged portion, a complementary hemispherical member marginally fitting within said recess and forming, together with the rotatable hemispherical roller, a spherical shell, said complementary hemispherical member having an aperture therein, an attachment member, a spindle secured to said attachment member and extending through said aperture, a bearing sleeve rotatably fitting said spindle, a lug projection integral with the bearing sleeve, an axle secured to said lug projection and offset from and inclined with respect to said spindle, a hollow boss on the rotatable hemispherical roller rotatably fitting the axle, said spindle having a collar and said hollow boss having a circumferential flange, and a retaining member disconnectably fixed to said lug projection and engaging said collar and flange to maintain the roller on the axle and the spindle in the bearing sleeve.
2. A caster comprising a rotatable hemispherical roller having its edge portion enlarged to form a peripheral floor-engaging tread and a recess within said enlarged portion, a complementary hemispherical member marginally fitting within said recess and forming, together with the rotatable hemispherical roller, a spherical shell, said complementary hemispherical member having an aperture therein, an attachment plate, a spindle secured to said attachment plate and extending through said aperture, a bearing sleeve rotatably fitting said spindle, a lug projection integral with the bearing sleeve, an axle secured to said lug projection and offset from and inclined with respect to said spindle, an axial sleeve integral with the rotatable hemispherical roller rotatably fitting the axle, a circumferential flange on said spindle and on said axial sleeve, and a retaining plate disconnectably fixed to said lug projection and engaging said circumferential flanges to maintain the roller on the axle and the spindle in the bearing sleeve.
